AIR COMPRESSOR HOUSING

Thomas L. Eaul, Toronto, Ontario, Canada, Lawrence P. Feer, Kazenovia, N.Y., and Hugo Magl, Etobicoke, Ontario, Canada, assignors to The Coleman Company, Inc., Wichita, Kans.

Filed Jan. 24, 1974, Ser. No. 436,120

Term of patent 14 years

Int. Cl. D15—02

U.S. Cl. D65—1 A

FIG. 3

FIG. 4

FIG. 5

FIG. 6

FIG. 7

FIG. 1 is a side elevational view of an air compressor housing showing our new design, the opposite side being the same as the side shown;

FIG. 2 is an end elevational view thereof, the opposite end being the same as the end shown;

FIG. 3 is a top plan view thereof;

FIG. 4 is a bottom plan view thereof;

FIG. 5 is a cross sectional view taken on line 5-5 of FIG. 1;

FIG. 6 is a cross sectional view taken on line 6-6 of FIG. 1; and

FIG. 7 is a cross sectional view taken on line 7-7 of FIG. 1.

We claim:

The ornamental design for an air compressor housing, as shown and described.
